UNITED STATES PATENT OFFICE

2,345,352

APPARATUS AND METHOD OF PRODUCING
PRODUCTS FROM UNDERCOOLED MOLTEN
METAL

Joseph M. Merle, Pittsburgh, Pa.

Original application July 1, 1938, Serial No.
216,968. Divided and this application November
14, 1941, Serial No. 419,118

7 Claims. (Cl. 22—57)

This invention relates to apparatus and methods of producing products from undercooled molten metal.

This application is a division of application Serial No. 216,968, filed July 1, 1938, now Patent No. 2,285,740, which is a continuation in part of Patent No. 2,129,702 which issued September 13, 1938.

While the procedure and apparatus disclosed in my Patent No. 2,129,702 and the products produced are eminently satisfactory, I have, nevertheless, discovered through further studies and investigations that, by making certain modifications as hereinafter described and claimed, ap- pertaining to the apparatus there described by me, I make it possible to produce new and commercially important solid products which are characterized by excellent physical properties and by a special new primary crystal structure.

It is, accordingly, one of the objects of my present invention to provide apparatus which is especially suitable for the production of new products from undercooled molten materials.

Another object of the invention resides in apparatus which is simplified as compared with previous apparatus and which is subject to close and accurate control, thus giving new and additional advantages over such prior apparatus.

A further object of the invention resides in the provision of apparatus which mechanically and functionally represents advances over what has been heretofore developed in this art and which is sensitive to control factors and to the particular nature of the molten material handled thereby, in which connection the apparatus is susceptible of adjustment so as to vary the so-called undercooling period.

A still further object of this invention is the discovery and definition of means and conditions for the continuous treating of molten metals and alloys preliminary to their introduction into a forming means to produce and control a definite state of undercooling such as will induce and create in the finished solid metal product a fine, uniform and homogeneous new primary crystalline structure.

Another object of this invention is the description of commercial machinery and equipment developed to continuously undercool under controlled conditions molten metals and alloys or non-metallic materials previous to their introduction into forming means, and to subsequently introduce or force the undercooled metal or alloy without any change in its condition or composition into the forming means in the form of a

thin consolidated stream projected under controlled velocity to produce metal products with the above homogeneous fine crystalline structure.

5 Another object of the invention is the production of metal products of many kind from metals and alloys in a controlled undercooled state or within their plastic range and not from metals and alloys in their molten state.

Another object of this invention resides in procedural features and steps for continuously treating metals and alloys in their molten state to place them in any desired state of undercooling and in that state of undercooling to introduce them into a forming means without disturbing, affecting, or modifying their original homogeneous chemical composition or inherent characteristics in any manner and without any contact with or contamination by outside gases or air, none being required or used for cooling, propelling, or impacting purposes in this invention.

Other and further objects and advantages reside in the various combinations, subcombinations, and details of construction hereinafter described and claimed and in such other and further matters as will either be understood by those skilled in this art or will be apparent from the following description.

In the accompanying drawing, the figure is a vertical sectional view, partly in elevation, of an apparatus adapted to mold or die cast individual products from a divided and recombined stream of molten metal or other molten material.

35 50 The method and metallurgical process present in the production of the products according to my present invention are clearly set forth in my Patent No. 2,285,740, of which this is a division, so will only herein be described in so far as is necessary to make my present invention readily understandable.

The term "undercooling" as used herein and as defined in physics is a condition which occurs when, at a definite temperature close to or under the crystallization point, equilibrium conditions are not reached; that is, the solid phase does not occur. Thus the metal is in a meta-stable condition. Researches in the undercooling of metals and alloys have shown that this condition may exist in metals undercooled 0.1° to 0.3° C.; for other metals such as gold, copper, bismuth, antimony, lead, tin, and a number of alloys undercooling may reach 30° to 45° C. so that all metals and alloys can be placed in an undercooled condition in which they retain most of the

mobility of a liquid, although part of the solid phase may be precipitated, and in that condition the metals and alloys flow and shape themselves in molds or dies.

To make clear the distinction between the molten and the undercooled states, above referred to, the molten state is that in which the molten metal or alloy is liquid and capable of flowing freely by gravity; its total heat content is the amount of heat required to bring it to its fusion point plus the amount of heat required for its latent heat of fusion plus the extra amount of heat put in as superheat for commercial handling which may range from a few degrees F. to 200 to 300 degrees F. as in the case of steel or alloy steel or other high melting point metals or alloys. The undercooled state as applied to metals and alloys and which I propose to establish and control is a condition which results from treating any molten metal or alloy as produced by present commercial furnaces to remove from it all its superheat of fusion and all or most of its latent heat of fusion to bring its temperature either close to its crystallization point or slightly therebelow for metals and alloys having a long plastic range before the treated metal or alloy is introduced or forced or propelled into a mold or die or between rolls at a definite velocity. This undercooled metal or alloy introduced into molds or dies or between rolls in that condition has still most of the mobility of a liquid and will, under the velocity at which it is propelled, readily shape itself to the contour of molds or dies. It is further characterized by the fact that each of its minutest component particles has already a crystal nucleus extending to part or to the whole of each particle depending upon how much of the solid phase has been precipitated as controlled by the degree of undercooling. These undercooled particles propelled in a stream into a mold or die will simultaneously conform to the contour of the mold or die to fill it and practically spontaneously crystallize from an infinite number of crystal nuclei throughout the whole mass of the formed product, which creates in the formed product a crystalline structure made of very small stringer-like at random crystals homogeneously and uniformly distributed throughout the whole solid metal product, this being strikingly different from the primary structure obtained from molten metal or alloy as described hereinbefore.

A stream of molten metal discharging onto a rapidly moving surface gives rise to certain definite actions. When such a stream of molten metal or other molten substance flowing out of a furnace spout or pouring nozzle at the normal pouring temperatures industrially used and at a certain rate of velocity of flow—as determined by the head of metal in the receptacle, ladle, or furnace which contains it or as governed by mechanical pumps or valves which propel it out of the container—is intercepted by a clean, colder solid metal or non-metallic surface free of moisture moving at a uniform rate of speed greater than the velocity of flow of the molten metal stream, a continuous area of contact is created at the intersection where the liquid and freely mobile metal or substance instantaneously shapes itself to the solid moving surface. This I term a wetting action. Under these conditions the molten or liquid metal is instantaneously and continuously carried away from the main body of the liquid stream, being pulled away from under it in a layer adhered to the moving sur-

face. This layer is hydrostatically self-leveling while being carried across the molten stream and carries with it as much of the molten metal or substance as it can attract under its intrinsic forces of atomic attraction and molecular cohesion. There is thus formed from the molten metal stream a continuous film or layer of uniform section and thickness which is adheringly carried by the solid moving surface to which the film or layer gives up heat from the instant contact is established.

The cross-section of this molten metal film is directly determined and controlled by the following relation:

Its cross-sectional area multiplied by the velocity of the moving metal surface carrying it is equal to the cross-sectional area of the molten metal of the molten metal stream multiplied by its velocity of flow.

For example, if a stream of molten metal flowing from a rectangular nozzle 2 inches wide by $\frac{1}{2}$ inch thick at a velocity of 2 feet per second is laid upon a metallic surface moving at 50 feet per second, or 25 times as fast, the molten metal film will have a section as follows: 2 multiplied by $\frac{1}{2}$ multiplied by 2 and divided by 50 equals .04 square inch, and the thickness of the film will be .04 divided by 2 inches or .020 inch.

From the foregoing, it is clear that any definite amount of heat content can be removed from any molten metal or other film either to cool it slightly, to undercool it to any desired degree or to completely solidify it in such manner that the film can be continuously used when it reaches the desired temperature or undercooled condition. The latter, as stated, results from a definite time and length of contact with the moving surface. The fully formed film is continuously separated from the moving cooling surface at a precisely predetermined point after it has had a definite length of contact with such surface. As the film is removed it is continuously directed to and introduced into a mold or die prepared to receive it.

By undercooling the molten alloy to the point where it will spontaneously crystallize throughout the mass of the solid product formed, in accordance with my invention, the original homogeneous composition of the alloy in the molten state is fully retained in every one of the minute crystals formed and such is retained after mechanical working and heat treating. This entirely new and different structural crystalline condition considerably increases the known intrinsic properties of these alloys and widens the field of their usefulness.

Referring now to the drawing, the figure illustrates a form of cooling and impacting machine in which the metal propelling and cooling surfaces used are the faces of two closely spaced rapidly rotating cooled cylinders or rolls. A main frame casting 51 supports two stationary shafts 52 and 53 upon which yoke pieces 54 and 55 are mounted for swinging movement in a vertical plane. A yoke end 56 of yoke piece 54 forms a mounting for a water cooled ring 57. Said ring is connected by hollow arms 58 and 59 to a hub 60. The ends of said hub are in the form of a hollow shaft 61 and are supported in bearings 62 of the yoke 54. This shaft 61 extends beyond the sides of the yoke 54 and the ends thereof swing in spaced slots 63 formed in the sides of the main frame casting 51. A gear 64 is keyed to one extended end of the shaft 61 and has substantially the same pitch diameter as the di-

ameter of the ring face 57a of the ring 57. When ring 57 and gear 64 are in an operating position, as shown, the gear 64 will mesh with a pinion or gear 65, which may be driven from a suitable variable speed drive (not shown). The drive to said pinion is such that said ring 57 may be rotated in the desired direction and at the desired peripheral speed.

Water or other liquid coolant is conducted through hollow arms 58 to the water-jacketed section of ring 57, and, flow being limited by baffles 66 and 67, is exhausted by conduits 68 and 69 in each arm 59. The coolant is thus returned to shaft 61 which has water intake connections at one end and water offtake connections at the other end to provide for the continuous circulation of water or other coolant.

Similarly, in the yoke end 70 of yoke piece 55 there is supported a water-cooled ring 71 connected by hollow arms 72 and 73 to hub 14 whose ends in the form of hollow shaft 75 are supported in bearings 76 of yoke 55. This shaft 75 extends outside of yoke 55, the extensions being free to swing in slots 77 formed in opposite sides of the main frame casting 51. On the extended end of shaft 75 there is keyed or secured a gear 78 of the same or about the same pitch diameter as ring face 79 of ring 71. When this ring 71 and gear 78 are in operating position, as shown, the gear 78 will mesh with gear 64, the rotation of which will rotate the face 79 of ring 71 in the opposite direction from and at the same peripheral speed as ring face 57a of ring 57. Ring 71 is cooled by water circulation in the same manner as already described in connection with the ring 57.

Yoke pieces 54 and 55 have an extended arm 54a and 55a, respectively, as shown. A rod 80 supporting a plate 80a at the bottom is attached to each of these arms. Grooved weights 81 rest on plates 80a and can be so adjusted as to counterbalance the yokes 54 and 55, the rings 57 and 71 and their gears under a positively adjusted load. With the arrangement just described the rings 57 and 71 are floatingly mounted to separate and permit foreign material, such as slag, to pass therebetween.

The width of face 79 of ring 71 and face 57a of ring 57 is suitably made or selected in each case for the width of metal film desired to be produced. The thickness of these cylindrical faces and the material of which they are made, for example, steel, cast iron, copper, or other high heat conductivity metals, are so selected and determined as to remove a definite amount of heat from films of various molten metals or substances of various thickness which are to be formed and carried thereon for definite and adjustable lengths of contact as governed by the factors above explained. As previously indicated, the surface condition of these faces 79 and 57a can be made such as will appropriately influence the rate of heat conduction from the molten metal film depending upon the results desired in any given instance. The diameter of rings 57 and 71 is made large enough so that the heat conducted to any portion of faces 57a and 79 will be dissipated from it by the cooling system before that portion again receives molten metal.

A receptacle 82 is positioned over the upper bight between rings 57 and 71 by means of brackets 83 of frame 51. This receptacle is adapted to receive molten metal or other molten substance from a melting furnace or ladle, not

shown, and to maintain a molten supply for operating purposes. It may have a stopper 84 actuated by a goose neck and operating lever of known construction to open and close nozzle 85.

Thus a continuous stream of molten material may be discharged through the nozzle 85 or successively regulable amounts of molten material may be intermittently discharged.

Under the receptacle 82 I provide a distributing chamber casting 86 in the form of a closed rectangular channel. This chamber casting is wider than the faces of the rings and has the two faces opposite these rings machined complementarily to the radius of the rings. There is a slot in the middle of the casting made to correspond to the maximum width of film to be formed by the machine but narrower than the width of faces 57a and 79 so that the edges of the slot will leave enough surface bearing against the ring faces to insure a perfect air seal between the casting 86 and said ring faces when these rings are rotated. This arrangement provides an opening of definite size between the ring faces at their points of contact. Recessed or grooved sides 87 are provided in the casting 86 which serve to confine or retain in place a side packing, thus further sealing the edges of rings 57 and 71. Inside of casting 86 I provide a cored casting 88 which forms a rectangular chamber having two slots 89 and 90 of selected width and thickness.

The metal stream 91 from nozzle 85 flows through the rectangular chamber, which is preferably lined with refractory material, and is divided into two equal streams which discharge through the said slots 89 and 90. Each of these streams contacts one of the ring faces 57a or 79, shapes itself thereto and is carried by it in the form of a separate film 92 or 93, the dimensions of which correspond to the supply slots 89 and 90. Both films travel at the same speed for a definite length of contact with the cylindrical cooling faces, this length having been previously calculated and then secured by appropriately adjusting the positions of the feeding slots 89 and 90 so that the required amount of heat will be removed from the films at the instant the predetermined length has been traveled. When reaching that point the two separate films are caused to aggregate or consolidate into a single recombined film or strip 94. This may be done by setting the space between ring face 57a and 79 equal to the total thickness of the two films. The further travel of the consolidated film is along a vertical straight line as will be understood from the drawing.

This film 94 travels in the direction stated through bottom channel chamber 94a absolutely free from air contact and friction against the walls of this channel; consequently, in an unbroken, undivided and unoxidized form it reaches the feeding opening of a mold or a die 95 to impact and shape itself under its velocity of motion to the contour of the cavities or impressions 96 of this mold or die.

A duct or pipe 97 leads to the space 98 to exhaust air from it so as to carry out the whole operation in a vacuum or to circulate or introduce gases of various compositions thereto when it is desired to operate in a special atmosphere to induce a desired chemical reaction with the film or films of molten metal.

While mold or die 95 may be of any suitable form and construction, I have illustrated one in two parts, each of which is connected by a rod 99 to an air or hydraulic piston indicated at 100.

The die is provided with core plates 101 and ejector pin plates 102. It is to be understood, however, that other types of molds or dies may be supplied by this machine such as ingot molds, sand molds or continuous molds. The machine of the drawing can be designed for such size or capacity as will form, cool and direct a thick consolidated film at relatively low speed into a mold or it can be made of such size that it will withstand high peripheral wheel and face speeds to form two very exceedingly thin metallic films only a few thousandths of an inch in thickness and propel the film consolidated therefrom into dies or mold cavities without any frictional loss of speed at velocities unobtainable with present die casting machines. The die-cast or other products will, moreover, be characterized throughout their entire mass by the new and desirable primary chill structure hereinabove described.

The foregoing is intended as illustrative rather than restrictive, and I may make suitable changes therefrom without departing from the spirit and scope of the invention.

I claim as my invention:

1. In an apparatus for undercooling molten metal and producing solid metal products of a primary crystal structure therefrom, a frame, a pair of rolls mounted on said frame for rotational movement with respect thereto about a pair of parallel spaced horizontal axes, means for driving said rolls at the same speeds in opposite directions, means for discharging a consolidated stream of molten metal onto at least one of said rolls in such a manner that at least one of said rolls will undercool and shape said stream of molten metal into a thin film and discharge said film by impact into a forming member disposed beneath said rolls, and a separate floating mounting for each of said rolls, urging said rolls towards each other to provide a predetermined relatively thin spacing between said rolls, but permitting movement of said rolls away from each other.

2. In an apparatus for undercooling molten metal and producing solid metal products of a primary crystal structure therefrom, a frame, a pair of rolls mounted on said frame for rotational movement with respect thereto about a pair of parallel spaced horizontal axes, means for driving said rolls at the same speeds in opposite directions to form a downwardly moving path between adjacent surfaces of said rolls, means for discharging a quiescent consolidated stream of molten metal onto said rolls in such a manner that said rolls will undercool and draw out said stream of metal into a thin film and accelerate and discharge said film at a high velocity, a separate floating mounting for each of said rolls, permitting movement of said rolls away from each other to permit the passage of foreign material therebetween, and means for yieldably urging said rolls towards each other to provide a predetermined thin path therebetween during normal operation thereof.

3. In an apparatus for undercooling molten metal and producing solid metal products therefrom, a frame, a pair of rolls, a receptacle for molten metal mounted on said frame over the bight between said rolls, a plurality of outlets in said receptacle, each of said outlets leading to the periphery of one of said rolls above the bight between said rolls, so said rolls will draw out and accelerate and undercool separate streams of metal and reconsolidate said streams of metal

into a thin film and discharge said film of metal at a high velocity in an undercooled condition into a shaping member placed below the bight between said rolls, means for mounting said rolls on said frame for rotational movement with respect thereto about a pair of parallel spaced horizontal axes and for movement towards or from each other, and other means for yieldably urging said rolls towards each other to provide a predetermined thin spacing therebetween, but permitting movement of said rolls away from each other, to permit the passage of foreign material therebetween.

4. In an apparatus for undercooling and producing solid metal products from undercooled molten metal, a main frame, a pair of rolls rotatable about a pair of parallel spaced horizontal axes, means for mounting said rolls on said frame for bodily movement towards or from each other, means for driving said rolls at the same speeds and in opposite directions, a receptacle for molten metal mounted on said frame over the upper bight between said rolls, an orifice in the bottom 20 of said receptacle, a chamber below said receptacle, said chamber having spaced outlets adapted to discharge the molten metal onto said rolls and merging into a single outlet in registry with the receptacle orifice, said chamber having opposite faces substantially conforming to the arcs of said rolls and said rolls being adapted to contact said opposite faces in an air tight manner, and means for urging said rolls in a direction towards each other and for normally maintaining said rolls in contact with said opposite faces of said chamber.

5. In an apparatus for undercooling and producing solid metal products from undercooled molten metal, a main frame, a pair of swingable yokes mounted on said main frame for movement about a pair of parallel spaced horizontal axes, a roll rotatably mounted on each yoke, adjacent the end thereof opposite from said pivotal mounting, means for driving said rolls at the same speeds and in opposite directions, a receptacle for molten metal mounted on said frame over the upper bight between said rolls, an orifice in the bottom of said receptacle, a chamber below said receptacle, said chamber having spaced outlets merging into a single outlet in registry with the receptacle orifice, said rolls being adapted to contact said chamber in an air tight manner, and means for normally maintaining said rolls in contact with said chamber.

6. In an apparatus for undercooling molten metal and producing solid metal products of a primary crystal structure therefrom, a frame, a pair of rolls mounted on said frame for rotational movement with respect thereto about a pair of parallel spaced horizontal axes, means for driving said rolls at the same speeds in opposite directions, a receptacle for molten metal disposed above the upper bight between said rolls, means for gravitationally discharging a stream of molten metal from said receptacle and dividing it into two parts and causing each part to engage one of said rolls and to be accelerated and be drawn by said rolls into an undercooled film moving at a high velocity and be recombined at the bight between said rolls into a composite film, and be discharged by said rolls at a high velocity to be shaped by impacting in a die or mold.

7. A method of making a metal product hav-

ing a primary crystal structure of a regulated number of uniformly distributed crystal nuclei, which consists in gravitationally discharging a stream of molten metal and subdividing this stream into two streams, intercepting each such stream by a rapidly moving cool clean metallic surface, forming each such stream into a thin film by said metallic surfaces and accelerating

and undercooling each such film and reconsolidating these streams into a single film travelling at a high velocity, and discharging said film into a forming member and forming said film to the form of said member by its impact of discharge from said surfaces.

JOSEPH M. MERLE.
